UNITED STATES PATENT OFFICE.

WILLIAM E. BRYAN, OF AKRON, OHIO.

SIZING OR SEPARATING APPARATUS.

1,339,161.

Specification of Letters Patent.

Patented May 4, 1920.

Application filed September 30, 1916. Serial No. 123,119.

To all whom it may concern:

Be it known that I, WILLIAM E. BRYAN, a citizen of the United States, residing at Akron, in the county of Summit and State of Ohio, have invented new and useful Improvements in Sizing or Separating Apparatus, of which the following is a specification.

This invention relates to a sizing or separating apparatus for mechanically sizing or separating granular material of different sizes or dimensions, and particularly to mechanical sizing apparatus of that class which dispenses with the use of screens and mechanically separates the particles of material of different sizes according to their size or volume.

The object of the invention is to provide a simple, reliable, and efficient construction of separating apparatus which may be inexpensively made and operated, and which will rapidly separate or classify solid granular material of all kinds into its components of different sizes.

A further object of the invention is to provide a sizing or separating apparatus in which the parts are readily adjustable to vary their action as required according to the nature of the material under treatment.

With these and other objects in view, the invention consists of the features of construction, combination and arrangement of parts hereinafter fully described and claimed, reference being had to the accompanying drawings in which:

Figure 1 is a side elevation with parts broken away of an apparatus embodying my invention.

Fig. 2 is a vertical transverse section 40 through the apparatus.

Fig. 3 is a top plan view of the supporting frame or carriage.

Fig. 4 is a view of one of the decks on an enlarged scale.

Figs. 5 and 6 are cross sections thereof on lines 5-5 and 6-6 of Fig. 4.

Fig. 7 is a view of one of the feed boards on an enlarged scale.

Figs. 8 and 9 are detail sections thereof on lines 8-8 and 9-9 of Fig. 7.

Figs. 10 and 11 are perspective views of one of the shoes and the coacting track rail.

Figs. 12 and 13 are detail views of one of the collectors.

In carrying my invention into practice, I provide a separator including a rectangular

or oblong rectangular frame or carriage 1 comprising side bars 2 and end bars 3, said side and end bars being suitably united and reinforced at the corners of the frame by diagonal braces 4. The frame or carriage is mounted for reciprocating motion at an angle to the horizontal upon base supports formed by I-beams 5, which may be secured to a floor or other foundation and which carries track rails 7, to be engaged by sliding shoes 8, upon the side bars of the carriage. As shown, the rails 7 are provided with V-shaped longitudinal grooves 9 receiving correspondingly shaped ribs or retaining projections 10 upon the shoes 8, whereby the shoes are held in guided connection with the rails from any liability of lateral displacement. The meeting faces 11 and 12 of the rails and shoes incline in opposite directions, the surfaces 11 extending at an upward and forward and the surfaces 12 at a downward and rearward angle of inclination to the horizontal, whereby in the back and forth reciprocations of the frame 65 or carriage said frame or carriage will move both vertically and horizontally, as will be readily understood.

In practice, any suitable means may be provided for reciprocating the carriage, the 75 means employed being preferably of a type for moving the carriage forward at a uniform rate of speed and retracting or moving it backward suddenly with a jerk or accelerated speed. In the present instance I 90 have shown the carriage connected at its rear end with a rod 13, spring pressed in one direction, and having a terminal roller to be engaged by a cam member, to illustrate a conventional manner of operation.

Supported by the carriage are one or more inclined separator decks or platforms 15, two of which are shown in the present instance, said decks or platforms being disposed at the opposite sides of the platform 100 and having their upper edges disposed in approximate relation, the surfaces of the decks or platforms thence extending downwardly and outwardly at a diverging angle of inclination of a desired degree. The 105 decks or platforms are provided at their upper ends with brackets 16, which are hingedly or pivotally connected, as shown at 17, to permit the decks to be relatively adjusted, and adjacent to their lower ends 110 the decks carry brackets 18 which are hingedly or pivotally connected, as at 19 with

adjustable supporting bars 20. These bars 20 are arranged adjacent the opposite ends of the decks and rest upon the end bars 3 of the carrier frame, said supporting bars 5 being provided with longitudinal slots 20 for the passage of fastening bolts 21, whereby they are mounted for sliding adjustment on the carrier frame and so as to be fixed firmly in adjusted position. The inner ends 10 of each pair of supporting bars 20 are provided with upturned portions 22 formed with threaded openings for the passage of the opposite ends of a shaft 23, said ends of the shaft being right and left hand threaded, 15 ed, respectively, and the central portion of said shaft being provided with a hand wheel 24 arranged between bearing and stop brackets 25, whereby by turning said wheel in one direction the brackets may be slid 20 outwardly to spread the lower portions of the decks, while by turning the wheel in the opposite direction the brackets will be slid inwardly to draw the lower portions of the decks toward each other. By this means 25 the hinged decks may be relatively adjusted to vary their slope or angle of inclination, as may be required or found advisable in the treatment of different materials, and it will be seen that the construction described 30 adapts both tables to be easily and conveniently adjusted to equal degrees in unison in a practically instantaneous manner.

Each separator deck or platform is reinforced on its inner side by suitably arranged longitudinal braces 26, and is provided with an outer separating surface to effect the sizing of the material or materials under treatment. To this end, the said outer surface of the deck or platform is provided 35 with a continuous series of spaced, parallel, longitudinal riffles 27, each consisting of a strip of rubber, wood, metal or other suitable material. These strips are of maximum width and depth at their rear 40 ends and thence gradually and uniformly taper in width and depth toward their forward ends, at which they are of minimum width and depth, by which construction retaining channels of flaring width and depth 45 are formed upon the surface of the deck for the reception of the material which is being acted upon, said channels being separated by the partitions or riffles over which the material flows in its course of travel downwardly and forwardly along the surface of 50 the deck.

For coöperation with the separator decks or platforms, I provide feed boards 28, said boards being mounted above the upper rear 55 portion of the separator decks in an inclined position, the two boards, one for each deck, being disposed opposite each other and having their inner or working surfaces inclining downwardly and inwardly toward 60 the upper edges of the decks at a reverse

angle of inclination to the angle of inclination of said decks. The lower edges of these boards are hinged or pivoted to the upper edges of the decks, as shown at 29, and at their rear ends the boards are provided with 65 hinged bracket arms 30 which depend therefrom and are formed with longitudinal slots 31 receiving bolts 32 upon the decks, whereby the boards are slidably connected with the decks to vary their angle of inclination, 70 nuts 33 being provided upon the bolts for clamping the bracket arms 30 to hold the boards disposed at the desired working angle of inclination. Each board is arranged to extend at an oblique angle to the line of 75 feed of the material, having its receiving end located outwardly and rearwardly beyond the rear end of the deck, and extending inwardly and forwardly at an angle to such portion of the deck, for the travel of 80 the material from a supply or feed conductor 34 to the deck at a corresponding angle. For this purpose, the board is made of approximately triangular form, and at 85 its forward portion or apex connects with a funnel shape nozzle 35 communicating with a feed pipe or trough 36, secured to the upper longitudinal edge of the deck, and through which the material is supplied to the deck, the pipe being open or perforated 90 at the bottom for the discharge of the material. Hence it will be understood that in the forward movement of each deck and its feed board the material will be fed forward to the deck for treatment. In practice 95 100 the surface of the feed board is preferably provided with riffles 37 corresponding in form and arrangement with the riffles of the deck, whereby in the initial feed of the material to the deck a primary separating action will be set up to distribute the material 105 properly to the surface of the deck for a continuation of such separating action, by means of which the necessity for the use of decks or separating surfaces of excessively 110 large size will be avoided.

In the operation of the separator as thus far described it will be understood that the material will flow over the rifled surfaces of the feed boards to the nozzles 35, through 115 which the coarse material and a portion of the finer material will discharge into the channels formed by the riffles at the upper rear portions of the decks, a portion of the fines, preliminarily separated from the coarse particles by the riffles of the feed 120 boards, entering the pipes or troughs 36 and passing forwardly along the same and discharging at the forward ends thereof into a suitable receptacle. In the back-and-forth 125 movements of the separator the material supplied to the decks will be agitated and constantly fed forwardly, the coarser material flowing at once over and down the rifled surfaces at the rear ends of the decks, 130

while the finer material progressively moves forward through the channels of constantly increasing widths and decreasing depths formed by the tapered riffles, as a result of 5 which the particles of material are caused to break or discharge over the riffles at different points along the line of feed and to discharge according to their degrees of fineness, at the bottom portions and at different 10 points along the length of the decks, the finest materials passing the full length of the decks and discharging at the forward ends thereof. It will thus be apparent that a grading operation is obtained by means of 15 which the granular particles will be progressively and gradually separated in accordance with their size or volume and without regard to their specific gravity, an efficient separation action of the grains according 20 to their grades or sizes being thereby efficiently obtained. This separating action is promoted by a relatively slow forward motion of the separator and a quick abrupt backward motion thereof, by which the material 25 is caused to feed forward with positiveness and certainty. By the use of a track structure of the character described it will be evident that the vertical as well as the longitudinal reciprocatory motion of 30 the separator will be secured without the use of toggle lever lifting mechanism, whereby the construction is simplified and the cost of maintenance reduced. The coarse and fine particles as they reach the 35 lower edges of the separating tables are discharged into funnel-shape discharge nozzles or collectors 38, each carried by a bracket arm 39 extending over the table and provided on its underside with a packing strip 40, of rubber or other suitable material, notched to receive the riffles, by which the arm may fit closely against the separator deck and serve as a divider and deflector for guiding the material to the collector. 45 The bracket arms are tacked or otherwise secured to the surface of the deck and may be arranged at suitable points along the same according to the character of the division and nature of the material under treatment. It will be understood, of course, that 50 suitable final receptacles may be provided to receive the different grades of separated material and to facilitate their final collection in a separated condition.

From the foregoing description, taken in 55 connection with the drawing, it will be seen that my invention provides a sizing or classifying separator which dispenses with the use of screens which separate the material according to the size or volume without regard 60 to its specific gravity, and that by the described construction of the decks and riffles a superior grading action may be secured which may be regulated to suit the nature or character of the material under treat- 65 ment. Furthermore, it will be seen that the construction described provides a simple type of separator which may be easily and conveniently operated and manufactured and sold at a comparatively low cost. By 70 providing each deck with a rubber surfacing and making the riffles of rubber an effective separating action may be obtained for more reliably handling certain kinds of materials which are not so readily separated. 75 upon a smooth or polished surface.

I claim:

In a mechanical classifier or separator, an inclined reciprocating deck having longitudinally extending tapered riffles, a pipe ex- 80 tending along the crest of the deck and having a funnel-shape inlet, and an inclined feed board disposed above the upper rear portion of the deck and provided with riffles similar in character to those of the deck 85 and arranged to discharge portions of the material upon the table and into said pipe.

In testimony whereof I affix my signature.

WILLIAM E. BRYAN.
